UNITED STATES PATENT OFFICE.

CURT F. REIS, OF CHICAGO, ILLINOIS, ASSIGNOR TO WESTERN IGNITION CO., OF CHICAGO, ILLINOIS.

ROTOR FOR MAGNETOS.

Application filed June 7, 1927. Serial No. 197,214.

This invention relates to magnetos, particularly of the type employing a rotating permanent magnet and a stationary generating winding, and has special reference to the general improvement of the construction of the rotor of such devices, whereby the same may be more readily and cheaply assembled.

In the ordinary construction of rotors of the present type it is usual to employ a circular plate or disc which is attached to the free end of the magnet or magnets for the purpose of furnishing a support for the shaft and for centering the pole pieces. These plates are usually attached by means of screws or the like. Such structures are objectionable, in that the screws sometimes become loose, thereby permitting the disc to become detached or partly so, with the result that the mechanism is partly disrupted, if not entirely destroyed.

In prior types of magnetos the rotor pole pieces are usually formed integrally with the hub or boss of the rotor and thus necessitate the special construction of the entire rotor if the number of poles is to be varied or if their thickness is to be increased or decreased for the purpose of varying the strength of the magnetic field.

It is an object of the present invention to eliminate the objectionable features of magneto rotors as above referred to, and to this end the pole pieces, instead of being integrally formed on the base or hub portion, are separately formed and then assembled. Furthermore, the use of a plate or disc secured to the free ends of the pole pieces is obviated by employing a structure in which the shaft is cast integrally with a portion of the rotor structure.

A further object of the invention resides in the construction of a rotor having a perfect balance due to the fact that in its final form it consists of a solid mass of metal.

Other objects and advantages of the invention will be apparent from the following description when considered in connection with the accompanying drawing, in which:

Figure 1 is a perspective view of two separately formed parts of the rotor ready to be assembled.

Figure 2 is a longitudinal section through

the rotor, the shaft being shown partly in section and partly in side elevation.

Figure 3 is a transverse section taken on line 3—3 of Figure 2 and looking in the direction of the arrows.

Figure 4 is a perspective view of the complete device, and

Figure 5 is a view showing the laminations employed in the rotor structure.

Referring to the drawing in greater detail, the numeral 1 indicates the base or butt of the magnet, and consists of a thick disc of magnetic material, such as hard steel, provided with a centrally disposed aperture for the reception of a drive shaft 2 which is formed of bronze, brass or other non-magnetic material.

The rotor may be provided with any number of poles and the pole pieces may vary in cross sectional area to suit different installations. In the present embodiment of the invention four poles are illustrated and the pole pieces 3, also composed of magnetic material, are properly spaced about the base 1 by means of pins 4, each pole piece being provided with a shoulder 5 for a purpose to appear hereinafter.

For the purpose of reducing eddy currents and increasing the permeability of this portion of the magnetic field the pole pieces are provided with laminations of soft iron or steel. These laminations are clearly indicated in Figures 1, 3 and 5, and it will be observed that they completely encircle the poles from a point about midway of the length of the pole pieces to the free ends thereof. These laminations designated 6 and 6^a are of two forms, as shown in Figure 5. The diametrically opposed poles of the same magnetic polarity are connected by the duplex laminations 6^a, and, in order to prevent the poles of unlike polarity from being short circuited by contact with these laminations, a plurality of small laminations 6 are fitted on the poles between the sets of connecting laminations. As shown in the drawing, the duplex laminations 6^a are employed to connect one set of like poles (here shown as the south poles) from the shoulder 5 for about one-third of the distance to the free ends of the poles, and then several of the laminations 6 are placed on these same poles.

The north poles carry laminations 6 from the shoulder 5 to the point where the du-

plex laminations 6^a on the south poles end. The remaining ends of the north poles are then fitted with duplex laminations 6^a and the south poles with laminations 6.

- 5 It will now be clear that the south poles are connected by laminations 6^a from shoulder 5 to a point approximately one-third of the distance to the free ends of the pole pieces and then for a similar distance 10 both sets of poles carry laminations 6. The remainder of the north pole pieces are then covered by laminations 6^a and the south poles by laminations 6. Magnetic leakage between the unlike poles is reduced to an 15 unobjectionable amount by a proper choice of the number of laminations 6 which are inserted between the two sets of connecting laminations.

In constructing that part of the rotor comprising the drive shaft and the laminations 20 the latter are assembled in a mold with the proper cores, and molten brass or bronze is poured in to form the shaft 2 and the webs 9 which are to be positioned between the pole 25 pieces 3. This material upon solidifying fixedly secures the laminations to the webs 9 and to the shaft 2. The webs 9 are molded with the longitudinally-extending grooves 10 which receive ribs 11 formed on the sides 30 of the pole pieces 3 to aid the pins 4 in securing the pole pieces against the action of centrifugal force.

In assembling the rotor, threads 12 are first formed on the end of the shaft 2 and 35 the latter passed between the pole pieces 3 and through the aperture in base 1, the bronze webs 9, of course, taking positions between the poles and the laminations 6 and 6^a encircling the ends of the poles. A nut 13 is then threaded onto the end of the shaft 2, 40 thereby drawing the parts tightly together and bringing the laminations into close contact with the shoulders 5 on the pole pieces. This construction provides a rotor of substantially solid metal and comprising the 45 desired number of poles separated by webs of non-magnetic metal and provided with laminations secured in position by connectors located within the contour of the rotor itself. 50 Obviously a rotor so composed will be perfectly balanced due to the fact that it is composed of a solid mass of metal of cylindrical form.

From the foregoing description it will be 55 apparent that I have devised a novel type of rotor which may be readily fabricated, and which, due to the manner of attaching the poles, may be varied to suit varying requirements. Furthermore, it will be observed that 60 by the construction disclosed herein the many disadvantages of a separate plate hereinbefore referred to are avoided.

In accordance with the patent statutes, I 65 have described what I now believe to be the best embodiment of the invention, but I do

not wish to be understood thereby as limiting myself or the scope of the invention, as many changes and modifications may be made without departing from the spirit of the invention; all such I aim to include in the 70 scope of the appended claims.

What I claim as new and desire to secure by Letters Patent is:

1. A rotor for magnetos including a magnetic base plate, a plurality of spaced pole 75 pieces secured to said plate, laminations encircling a portion of said pole pieces, and a mass of cast non-magnetic metal intimately uniting said laminations.

2. A rotor for magnetos comprising a magnetic base plate, a plurality of spaced pole pieces secured to said plate, laminations encircling said pole pieces, a non-magnetic shaft, and a mass of non-magnetic material 80 intimately securing the laminations to the shaft.

3. A rotor for magnetos including a base plate, a plurality of separate pole pieces spaced about said plate, laminations of magnetic material surrounding the ends of said 90 pole pieces remote from said plate, and integral connections between certain of the laminations of the diametrically opposed pole pieces.

4. A rotor for magnetos including a base 95 plate, spaced pole pieces secured to said plate, a shaft, a plurality of webs integral with said shaft and positioned between said pole pieces, laminations encircling the ends of the pole pieces and connecting the like 100 poles, and means for securing said shaft to said base plate.

5. A rotor for magnetos including a base plate, pole pieces connected to said plate, a shaft, a plurality of webs integral with said 105 shaft and positioned between said pole pieces, and a tongue and groove connection between said pole pieces.

6. In a rotor including a base plate and a plurality of pole pieces, a shaft of non-magnetic metal, integrally formed longitudinal webs on said shaft, and a plurality of sets of metallic laminations secured to said webs and shaft and encircling the ends of 110 said pole pieces.

7. In a rotor including a base plate and a plurality of pole pieces, a shaft of non-magnetic metal, integrally formed longitudinal webs on said shaft, a plurality of sets of laminations of magnetic material secured 115 to said webs and shaft and encircling the ends of said pole pieces, and rigid connections between certain of said sets of laminations, said connections passing through said shaft.

8. A rotor for magnetos including a base plate, pole pieces connected to said plate, a shaft of non-magnetic metal, integrally formed longitudinal webs on said shaft, a plurality of sets of laminations of soft metal 120

secured to said webs and shaft, said shaft being passed through said base plate with the webs disposed between said pole pieces and the sets of laminations encircling said 5 pole pieces, and means for drawing said laminations into snug engagement with said pole pieces.

9. A rotor for magnetos comprising a circular base plate of magnetic material, a plurality of spaced pole pieces magnetically connected to one face of said plate, the diametrically opposed pole pieces being of like polarity, laminations encircling the ends of 10 said pole pieces and rigidly connecting the ends of the like poles, a shaft composed of non-magnetic metal, and a mass of non-magnetic metal intimately uniting said laminations with said shaft.

10. A rotor for magnetos comprising a

circular base plate of magnetic material 20 having an opening therein, a plurality of spaced pole pieces secured to one face of said plate around said opening, a plurality of stacks of laminations having openings therein, a shaft of non-magnetic material 25 carrying spaced integral webs intimately secured to said stacks of laminations, and means for securing said laminations in fixed relation about said pole pieces when said shaft is inserted in the opening in said base 30 plate with the webs between the pole pieces.

11. A rotor for magnetos including a base plate, a plurality of pole pieces about said plate and in contact therewith, laminations of magnetic material encircling said pole 35 pieces, certain of the laminations of opposed pole pieces being integrally connected.

CURT F. REIS.
